UNITED STATES PATENT OFFICE

2,329,886

CURTAIN ROD AND HANGER

Josephine Eckstine, Los Angeles, Calif.

Application December 12, 1941, Serial No. 422,728

(Cl. 211—105.2)

This invention relates to household furnishings and the like, and particularly pertains to curtain rods and hangers.

At the present time it is the practice to hang window curtains and side draperies over window openings, and in some instances to provide a closure for the window opening, such for example as a roller shade curtain or a Venetian blind. It is desirable to provide a curtain rod and hanger structure which will not interfere with the window closure member, such as a shade curtain or a Venetian blind, and which will support the ordinary window curtains and side draperies so that they may be manipulated separately if desired. It is the principal object of the present invention, therefore, to provide a curtain rod and hanger structure which includes a bracket substantially concealed in the frame of the window and upon which one or more curtain rods may be supported in spaced parallel relation to each other.

The present invention contemplates the provision of bracket plates adapted to be fixed within the jambs of the window frame and projecting therefrom to receive one or more curtain rods and to support said rods in parallel relation to each other.

The invention is illustrated by way of example in the accompanying drawing, in which:

Figure 1 is a view in perspective showing the application of the present invention.

Fig. 2 is an enlarged view in vertical section as seen on the line 2—2 of Fig. 1 and showing one of the bracket plates with the curtain rod removed.

Fig. 3 is a view in horizontal section as seen on the line 3—3 of Fig. 2 showing the manner in which the bracket plate is mounted with relation to the jamb of the frame and further disclosing the independent mounting of a curtain roller.

Fig. 4 is an enlarged fragmentary view in plan showing the assembly of two curtain rods and their mounting upon the bracket plate.

Fig. 5 is a view in perspective showing one of the extension brackets for the outer curtain rod and indicating a fragmentary portion of the inner curtain rod by dotted lines.

Fig. 6 is a view in vertical section through the bracket plate and inner curtain rod as seen on the line 6—6 of Fig. 3.

Referring more particularly to the drawing, 10 indicates the frame of a window having opposite vertical side facings 11. It is to be understood that the window may be of any desired type. It

may be desirable to temporarily close the window to the entry of light by the use of a roller window shade 12, such as indicated in Figs. 2 and 3. The roller shade is mounted on brackets 13 spaced inwardly from the face of the window frame as shown in Fig. 3. The side facings carry vertical batten strips 14, which, as shown in Fig. 3, have a forward edge lying flush with the face of a window frame. Secured between the body of the side facing 11 and a batten strip 14 adjacent to the top of the window frame are bracket plates 15. These plates are particularly shown in Fig. 2 of the drawing. Here it will be seen that the plates are formed with a fastening portion 16 which is covered by the batten strip 14. Extending horizontally from the portion 16 is an offset portion 17 which extends upwardly and overlaps the face of the window frame. Projecting horizontally from the offset portion 17 is a tongue 18. This tongue is substantially rectangular and lies in a vertical plane. Struck from the tongue is a tang 19 which is bent to lie partially out of the plane of the tongue so that it will frictionally engage the end sheath of the curtain rod into which the tongue projects. It will thus be seen that the bracket plates are of relatively small dimensions and may be concealed substantially while supporting the curtain rods.

By the use of the bracket plates 15 it is possible to support a single curtain rod 20 upon which sash curtains 21 are supported. The curtain rod 20 may be of the usual extensible type made from two complementary telescoping sections of sheet metal which are of channel shape. The sections have a straight horizontal portion, such as indicated at 22, and an end extension 23 which is disposed at right angles to the portion 22. The sectional formation of the rod is shown in Fig. 6, where it will be seen that the body of the rod is flat and that the opposite longitudinal marginal edges are bent upon themselves to form channels 24. These channels receive the tongues 18 of the bracket plates 15 while the tangs 19 frictionally bear against the body of the rod to hold the rod in its assembled and supporting position with relation to the bracket plate.

In some instances it may be desirable to support side draperies, as indicated at 25, as well as the sash curtains 21. This can be easily done with the present device by providing a pair of extension brackets 26. The extension brackets 26 are formed with a rigid bar 27 carrying a yoke 28 at one end and a rod seat 29 at its opposite

end. The yoke 28 provides a socket into which the end 23 of a curtain rod 20 may extend. The end 23 of the rod is free to receive tongue 18 of the bracket plate. Thus, the curtain rod 20 and the extension brackets 26 will all be supported upon the two bracket plates at opposite sides of the window opening. The rod seat 29 is here shown as being cylindrical and tubular. The member extends vertically and has a longitudinal slot 30 in its side wall. This slot terminates short of the lower end of the member 29, thus forming a supporting shoulder. Extending into the slot is the tapered end 31 of an outer rod 32. The outer rod 32, as shown in Fig. 4, lies in spaced parallel position with relation to the rod 20 and is in advance thereof in the same horizontal plane. The rod 32 is intended to be used as a support for side draperies 25 for the window. The rod 32 may be extensible in character and constructed in a manner similar to that of rod 20. The end portions of the rod, however, are straight and the channel sections have been flattened to permit the ends to be inserted into the slots 30 and to engage the walls of the slot frictionally so that the rod will be held in position.

In operation of the present invention the structure is assembled preferably by forming a relieved face 33 on the upper end of the batten 14. The length of this relieved portion agrees with the length of the section 16 of the bracket plate. The bracket plates are then secured in position against the face of the side facings 11 of the frame by screws or nails 34, after which the batten is secured over the portion 16 of the plate so that the tongues 18 will project outwardly and will be vertically aligned and parallel on the opposite side facings of the frame. If it is desired to only use the single curtain rod 20 it may be drawn out to a length appropriate to the width of the opening, after which the ends 23 are positioned over the tongues to abut against the edge of the extension 17. The tangs 19 will frictionally engage the body of the rod section and hold the rod in position. When it is desired to hang side draperies as well as the sash curtains the end portions 23 of the rod 20 are positioned within the yokes 28 of the extension brackets 26 so that they appear as shown in Fig. 5 of the drawing. The assembled rod and bracket structures are then positioned over the tongues 18 of the bracket plates 15. The rod 32 may then be placed in position with its ends 31 seated within the slots 30. It will be understood that as these rods are placed in position appropriate curtains or draperies may be hung on them.

It will thus be seen that the curtain rod and

hanger structure here disclosed comprises simple inexpensive concealed bracket plates carrying one or more rods which may be assembled and removed separately and which can be adjusted to any window opening.

While I have shown the preferred form of my invention as now known to me, it will be understood that various changes may be made in combination, construction, and arrangements of parts by those skilled in the art, without departing from the spirit of my invention as claimed.

Having thus described my invention, what I claim and desire to secure by Letters Patent is:

1. A curtain supporting structure, comprising a supporting bracket fixed to the side facing of a window and projecting from the face thereof, an extension bracket, a curtain rod carried at the outer end of said extension bracket, a second curtain rod on which the inner end of the extension bracket is mounted, said second rod engaging the supporting bracket, whereby the extension bracket and the two rods will be supported.
2. A curtain supporting structure, comprising a supporting bracket fixed to the jamb of a window and projecting from the face thereof, an extension bracket, a curtain rod carried at the outer end of said extension bracket, and a second curtain rod on which the inner end of the extension bracket is mounted; said second rod engaging the supporting bracket, whereby the extension bracket and the two rods will be detachably supported.
3. A curtain supporting structure, comprising a bracket plate mounted upon the side facing of a window frame, said plate having an outwardly projecting tongue standing in a vertical plane, a separate extension bracket formed at its inner end with a yoke to receive an inner curtain rod having an inturned end projecting into the yoke of the extension bracket and fitting over the tongue of the bracket plate.
4. A curtain supporting structure, comprising a bracket plate mounted upon the side facing of a window frame, said plate having an outwardly projecting tongue standing in a vertical plane to receive the end of an outer curtain rod, a separate extension bracket formed at its inner end with a yoke to receive an inner curtain rod having an inturned end projecting into the yoke of the extension bracket and fitting over the tongue of the bracket plate, and an outer curtain rod detachably secured upon the outer end of the extension bracket.
